UNITED STATES PATENT OFFICE.

EDGAR B. STOCKING, OF WASHINGTON, DISTRICT OF COLUMBIA; SARAH C. STOCKING
EXECUTRIX OF SAID EDGAR B. STOCKING, DECEASED.

CLOTHES-WRINGER.

1,251,301.

Specification of Letters Patent. Patented Dec. 25, 1917.

Application filed January 16, 1917. Serial No. 142,703.

To all whom it may concern:

Be it known that I, EDGAR B. STOCKING, a citizen of the United States, residing at Washington, in the District of Columbia, have invented certain new and useful Improvements in Clothes-Wringers, of which the following is a specification, reference being had therein to the accompanying drawing.

10 This invention relates to certain new and useful improvements in clothes wringers, and more particularly to mechanical means for automatically bodily separating the pressure rolls by the rotation thereof, when 15 they are separated abnormally by the insertion of a thick bunch of goods whereby the rolls will be instantaneously separated and the power cut off.

Another object of my invention is to provide means for bodily separating the rolls which is operated by one of the rotating parts of the wringer whereby the use of springs are eliminated and a construction is provided which enables the upper pressure 25 roll to be raised bodily with the pressure means away from the lower roll and without relieving the pressure on said upper roll.

Another object of my invention is to provide a releasing mechanism which can be 30 readily attached to the ordinary construction of clothes wringer now in use so as to convert the wringer into a safety wringer with means for separating the rolls and cutting-off the power so that in case of a foreign object being drawn between the rolls, the rolls will be instantaneously separated 35 and the rotation of the rolls stopped so as to prevent the foreign object from being drawn further between the rolls.

40 Another and further object of the invention is to provide a pressure roll releasing device which is carried by a top bar and normally held in predetermined position within the frame in such position that an ordinary 45 working space is provided for the rolls so that the machine can be used for wringing goods in the ordinary manner, said device being arranged within the path of travel of the upper pressure roll carrying shaft in 50 such a manner that when the rolls are separated abnormally the retaining means is released and at the same time a member is thrown into engagement with one of the revolving parts of the wringer so as to raise 55 the upper roll bodily away from the lower

roll, means being provided in connection with the raising means for cutting off the power when the upper roll has been raised.

Another and further object of the invention is to provide a construction of release 60 in which the upper pressure roll is held under pressure by the pressure means at all times whether in contact with the lower roll or out of engagement therewith which enables the device to be reset without adjusting the pressure means.

Another and further object of the invention is to provide a novel form of power shifter which throws the drive pulley or crank as the case may be out of engagement 70 with the gear of the lower pressure roll shaft in order to prevent the lower roll from rotating after the rolls have been separated.

Another and further object of the invention is to provide novel means for connecting the lifting means for the upper pressure roll so as to cause the roll to be lifted at 75 both ends simultaneously.

Other and further objects and advantages 80 of the invention will be hereinafter set forth and the novel features thereof defined by the appended claims.

In the accompanying drawings,

Figure 1 is a side elevation of a clothes wringer partly in section showing the application of my improved construction of pressure release and power control;

Fig. 2 is an end view of the same, the driving member being removed;

Fig. 3 is a side elevation partly in section 90 showing the position of the parts when the rolls are separated and the power cut off;

Fig. 4 is a perspective view of the upper portion of the wringer showing the upper pressure roll and the pressure means therefor connected as a unit in order to allow the device to be readily attached or detached from the wringer without changing the pressure;

Fig. 5 is a perspective view of one of the 100 lifting members detached; and

Fig. 6 is an end view showing a slightly modified form of pivoted latch having a rigid tooth employed in connection with the lifting member.

105

Like numerals of reference refer to like parts in the several figures of the drawings.

In carrying out my invention I employ a wringer frame 1 of the ordinary construction having the usual side bars 2 in the 110

lower ends of the slots of which are secured 2 bearings 3 carrying a shaft 4 having a pressure roll 5 which is adapted to be engaged by a coöperating upper pressure roll 6 carried by a shaft 7 working freely in the slots of the side bars. The shafts 4 and 7 carrying the pressure rolls are provided with meshing gears 8 and 9 at each end as clearly shown so as to cause the upper pressure roll 10 to be rotated from the gear of the shaft 4 which is adapted to be revolved by any suitable driving means, and I have herein shown the shaft 4 with the driving pulley 10 at one end loosely mounted thereon. The 15 driving pulley is formed with a groove collar 11 and a pin 12, said pin being adapted to extend into a recess 13 formed in the adjacent gear 8 in order to lock the pulley to the gear so that the lower pressure roll can be rotated. The drive pulley 10 with its clutch pin 12 is normally held into engagement with the gear 8 by a coil spring 14 surrounding the shaft 4 in order to hold the pin into the recess 13 of the gear so as to 20 form a driving connection between the members whereby the wringer can be driven. While I have shown a drive pulley for rotating the lower shaft it is, of course, understood that a gear or a crank could be 25 used for this purpose without departing from the spirit of my invention.

Mounted on each end of the pressure roll carrying shaft 7 within the slots of the side bars are bearings 15 carrying spring supports 16 on which are mounted coil pressure springs 17 engaged by bearing plates 18 which are preferably provided with position pins, said bearing plates being carried by the ends of a pressure bar 19 as 30 clearly shown in Fig. 1 so as to hold and guide the pressure springs in their movements within the frame. The bearing plates 18 of the pressure bar 19 are adapted to be engaged by pressure screws 20 mounted in 35 threaded boxes 21 carried by a movably mounted top bar 22 which is seated on shoulders 23 formed by enlarging the slots of the side bars 2 at their upper ends as 40 clearly shown in Fig. 2, said top bar being guided in its upward movement in the slots of the side bars as will be hereinafter fully described.

Secured to the ends of the movably mounted top bar 22 are lifting members 24 and 25 which extend down along the sides of the side bars 2 and are provided with elongated openings 26 to receive the ends of the upper pressure roll carrying shaft 7 and bifurcated lower ends which embrace 45 the ends of the lower roll carrying shaft 4. The lifting member 25 is provided at its lower end with a lateral projecting lug 27 formed on one of the legs of the bifurcations which is adapted to engage an arm 28 50 of a rock shaft 29 mounted in the bracket 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 the position as shown in Fig. 3. As the pivoted latches are moved upwardly the straight portions 39' thereof ride on the pins 35 in order to hold the teeth 38 thereof in mesh with the gears 8 until the same has traveled such a distance that the notches 40 of the latches ride over the stop pins which holds the parts in separated or raised position.

The edges of the notches 40 are slightly inclined as shown at 40' in order to allow the parts to be moved back into their normal positions by exerting pressure in the top bar as the inclined edge rides over the stop pin when pressure is brought to bear thereon and allows the parts to be reset.

The tail portions 37 of the pivoted latches are slotted as shown at 41 into which extend stud pins 42 carried by crank arms 43 mounted on a rock shaft 44 arranged with the lower portion of the frame of the wringer so as to cause the two pivoted latches to be moved in unison whereby the two lifting members 24 and 25 will be raised together so as to insure the raising of both ends of the upper pressure roll. As the lifting member 25 is carried upwardly by the rotation of the gear the lugs 27 strike the arm 28 of the rock shaft 29 and causes the shaft to be rocked in its bearing which moves the fingers 31 into such position that the driving member 10 is drawn out of engagement with the gear of the lower shaft so as to stop the rotation of the lower pressure roll.

In the modification shown in Fig. 6, 42 indicates the wringer frame, and 43 the lifting member which is mounted on the frame in substantially the same manner as shown in the preferred form. Pivotedally carried by 40 the lifting member 43 is a pivoted latch 44 which coöperates with a stop pin 45 for holding the parts in position as shown, said latch having a tail portion 46 provided with an integral offset tooth 47 which is adapted to be moved into mesh with the gear of the lower pressure roll shaft so as to raise the lifting member.

In the operation of a wringer as herein shown and described, assuming that the parts are in the position as shown in Fig. 1, and the driving member is being driven by any suitable means, the pressure rolls 5 and 6 are rotated so as to wring the clothes passing between the same. In case of a foreign object being drawn between the pressure rolls the upper pressure roll 6 is raised upwardly beyond the ordinary distance of travel in wringing clothes so as to cause the shaft 7 to be brought into engagement with the inclined faces 36 of the pivoted latches 32 which rocks the pivoted latches on their pivots so as to throw the inclined faces 34 of the latches out of engagement with the stop pins 35 and at the same time the pivoted teeth 38 are moved into mesh with the gears

8 of the lower pressure roll shaft 4, and as their shaft is being rotated the lifting members are raised vertically the teeth being held in mesh with the gear by the straight portions 39' of the pivoted latches. As the lifting members are raised vertically, the movable parts above the upper pressure roll are raised vertically as shown in Figs. 3 and 4 so that the upper pressure roll 6 is moved bodily away from the lower pressure roll 5, and the pressure means for said upper rolls is maintained in pressing position. As the lifting members continue their upward movement the pivoted latches ride over the stop pins 35 and hold the parts in raised position. As the lifting member 25 is raised vertically by the rotation of the gear the lug 27 carried by the lower end thereof is brought into engagement with the arm 28 of the rock shaft 29 so as to cause the fingers 31 to throw the driving pulley 10 outwardly so as to disconnect the driving connection between said driving pulley and gear which instantaneously stops the rotation of the lower pressure roll and as the gears of the upper pressure roll are out of mesh with the gears of the lower pressure roll, the pressure rolls are instantly stopped from rotation.

In operation I have found that in some instances the upper pressure roll 6 is only moved vertically at one end by the foreign object and to insure the raising of both ends of the pressure roll simultaneously I connect the lowered ends of the pivoted latches so that they are thrown into mesh with the lower gears simultaneously which causes the lifting members to be raised together so as to maintain the parts in horizontal position in their upward movement. When the movable parts above the upper pressure roll have been raised into the position as shown in Fig. 3, the pressure means is maintained on the upper pressure roll whereby the movable parts can be readily forced back into operating position by exerting a downward pressure on the top bar thereby overcoming the difficulties now existing in pressure releases in having to readjust the pressure on the pressure rolls after the release has been operated. When it is desired to remove the parts for any purpose by moving the finger 28 outwardly in the rock shaft 29 and drawing upwardly on the top bar, the upper pressure roll, bearings, pressure springs, pressure bar and top bar can be lifted vertically out of the wringer frame as shown in Fig. 4.

From the foregoing description it will be seen that I have provided a clothes wringer with an automatic pressure release and power control in which the pressure between the pressure rolls is instantaneously released by bodily moving the upper pressure roll away from the lower pressure roll so as to

move the gears out of mesh and at the same time the driving members used for rotating the lower pressure roll carrying shaft are instantly disconnected so that the rolls when separated are stopped from rotating.

I claim:—

1. In a machine of the kind described, the combination with pressure rolls and pressure means for said rolls, means actuated by the abnormal separation of said rolls for releasing the pressure between said rolls, and means actuated by the rotation of one of said rolls for bodily raising one of said rolls.
2. A clothes wringer, comprising a frame having pressure rolls and pressure means for said rolls mounted therein, lifting members for bodily raising said pressure means and one of said rolls, means carried by said lifting members for holding said rolls in contact under tension, and means actuated by the abnormal separation of said rolls co-operating with one of the movable parts of said wringer for actuating said lifting members.
3. A clothes wringer, comprising a frame having a fixed roll, a co-operating roll mounted in said frame and movable toward and away from the fixed roll, means for exerting pressure upon the movable roll, and means actuated by the abnormal separation of said rolls for releasing said movable roll and for moving the same bodily away from the fixed roll by the rotation of one of the movable parts of said wringer.
4. A clothes wringer, comprising a frame having a pressure roll mounted therein, a top bar carrying pressure springs and a pressure roll, movable as a unit in said frame, means for holding said top bar, pressure springs, and pressure roll in predetermined position within said frame, said last-mentioned pressure roll being movable toward and away from the first-mentioned pressure roll, and means released by the abnormal separation of said rolls for bodily raising said movable roll away from the fixed roll by the rotation of one of the movable parts of said wringer.
5. In a machine of the kind described, the combination with pressure rolls, a power control for said rolls, a driving connection between said rolls, means for exerting pressure upon one of said rolls, means for holding said rolls in contact under pressure, and means actuated automatically by the abnormal separation of said rolls for releasing said movable roll and for bodily raising said roll with its pressure means away from the fixed roll and disconnecting the power control by the rotation of one of said driving means.
6. A clothes wringer, comprising a frame having pressure rolls, one of said rolls being removably mounted in respect to the other roll, means for exerting the pressure

on said movable roll, means for holding said rolls in contact under pressure, and means actuated automatically by the abnormal separation of said rolls for releasing said retaining means and for bodily moving said movable roll away from the fixed roll by the rotation of one of the pressure rolls.

7. A clothes wringer, having a movable pressure roll, a fixed pressure roll, means for holding said pressure rolls in contact under pressure, means for exerting pressure against the movable roll, and means actuated by the rotation of one of said rolls for bodily moving said movable roll away from the fixed roll when said movable roll is moved to abnormal position.

8. A clothes wringer, comprising a frame having pressure rolls mounted therein, one of said rolls being movably mounted in respect to the other roll, means for exerting pressure against the movable roll, means for holding said rolls in contact under pressure, means for releasing said retaining means on the abnormal separation of said rolls, and means actuated by the rotation of said rolls for bodily raising said movable roll and pressure means away from the fixed roll.

9. A clothes wringer, comprising a frame, a pressure roll mounted in said frame, a co-operating pressure roll having tension means removably mounted in said frame as a unit, means for holding said pressure rolls in contact under tension, and means for bodily raising said movable roll away from the fixed roll by the rotation of one of the movable parts of said wringer on the abnormal separation of said rolls.

10. A clothes wringer, comprising a frame, a pressure roll mounted in said frame, a co-operating pressure roll removably mounted in said frame carrying pressure means, means for holding said pressure rolls in contact under pressure, and means actuated by the abnormal separation of said rolls for bodily raising said movable roll and pressure means away from the fixed roll by the rotation of one of the parts of said wringer.

11. A clothes wringer, having a pair of pressure rolls provided with meshing gears one of said rolls being movably mounted in respect to the other roll, means for maintaining tension upon said movably mounted roll, means for holding said pressure rolls in contact under tension, said means released by the abnormal separation of said rolls, and means actuated by the retaining means co-operating with one of the gears of said pressure rolls for bodily moving said movable roll away from the fixed roll.

12. A clothes wringer, comprising a frame having a pressure roll mounted therein, a co-operating roll movable toward and away from the fixed roll, means for exerting tension upon the movable roll, means for hold-

- ing said rolls in contact under tension and means for automatically bodily moving said movable roll away from the fixed roll by the rotation of one of said rolls on the abnormal separation of said roll. 13. A clothes wringer, comprising a frame having pressure rolls and pressure means for said rolls mounted therein, one of said pressure rolls and pressure means being bodily movable away from the other pressure roll, means for holding said rolls in contact under pressure, means actuated by the abnormal separation of said rolls for releasing said retaining means, and means actuated by the releasing means for bodily separating said rolls by the rotation of one of the moving parts of said wringer. 14. A clothes wringer, comprising a frame having a fixed roll, a movable roll having pressure means arranged to contact with said fixed roll, means for holding said pressure rolls in contact under tension, and means carried by said retaining means for bodily raising said movable roll by the rotation of one of the parts of the wringer when said movable roll is separated abnormally from the fixed roll. 15. A clothes wringer, comprising a pair of pressure roll carrying shafts provided with meshing gears, pressure means for said pressure rolls, means for holding said pressure means in predetermined position for maintaining tension between said rolls, said pressure retaining means being released on the abnormal separation of said rolls and provided with means engaging one of the gears of the pressure rolls for bodily raising one of said rolls by the rotation of said gear. 16. A clothes wringer, comprising a frame having pressure rolls and pressure means for said rolls mounted therein, one of said rolls being movable toward and away from the fixed roll, means for holding said pressure means in predetermined position, and means being released by the abnormal separation of said rolls and thrown in contact with one of the rotating parts of said wringer for bodily moving said movable roll away from the fixed roll. 17. A clothes wringer, comprising a frame, a top bar movably mounted in said frame carrying lifting members, said frame having pressure rolls and pressure means for said rolls, pivoted latches carried by said lifting members for holding said top bar in predetermined position within said frame, said latches being arranged in the path of travel of the shaft of one of said pressure rolls, and means carried by said pivoted latches engaged by one of the rotating parts of said wringer for raising said lifting members when said latches are released by the abnormal separation of said rolls. 18. A clothes wringer, comprising a frame having a fixed roll and a coöperating roll movable toward and away from the fixed roll, a top bar mounted in said frame, lifting members carried by said top bar having a connection with said movable roll, pressure means disposed between said top bar and movable roll, and pivoted latches carried by said lifting members for holding said top bar in predetermined position within said frame, said latches being operated by the abnormal separation of said rolls. 19. A clothes wringer, comprising a frame having a pressure roll mounted therein, a top bar movably mounted in said frame, lifting members carried by said top bar, a coöperating roll carried by said lifting members, pressure means disposed between said coöperating roll and top bar, pivoted latches carried by said lifting members for holding said top bar in predetermined position within said frame, said latches having inclined portions arranged in the path of travel of the shaft of the pressure roll carried by the lifting members, said pivoted latches having means engaging one of the revolving parts of said wringer when released by the abnormal separation of said rolls for raising said lifting members with the pressure roll and pressure means therefor. 20. A clothes wringer, comprising a frame having a shaft mounted therein carrying a pressure roll, a top bar movably mounted in said frame, lifting members carried by said top bar, a shaft movably mounted in said lifting members carrying a coöperating pressure roll, meshing gears carried by the shafts of said pressure rolls, pressure means disposed between said top bar and the pressure roll carried by said lifting members, stop pins carried by the frame of said wringer, pivoted latches carried by said lifting members engaging said stop pins for holding said top bar in predetermined position within said frame, said pivoted latches being arranged in the path of travel of the pressure roll carrying shaft carried by the lifting member, and means carried by said pivoted latches engaging one of the gears of the pressure roll shaft when said latches are moved by the abnormal separation of said rolls in position to release said pressure means. 21. A clothes wringer, comprising a frame having pressure rolls and pressure means for said rolls mounted therein, one of said rolls being movable toward and away from the other roll, means for holding said rolls in contact under tension, a driving member for one of said rolls, a power control for said driving member, and means actuated by the abnormal separation of said roll for simultaneously releasing the pressure between said rolls, raising said movable roll and operating said power control. 22. A clothes wringer, comprising a frame

- having a revoluble pressure roll mounted therein, a coöperating pressure roll movably mounted in said frame, means for exerting pressure thereon, means for holding 65
5 said pressure rolls in contact under pressure, a driving member for one of said rolls, a power control for said driving member, said pressure retaining means being released by the abnormal separation of said rolls, and
10 means actuated by the rotation of one of said rolls for bodily raising said movable roll away from the fixed roll and for operating said power control.
23. A clothes wringer, comprising a frame 15 having a pressure roll revolubly mounted therein carried by a shaft, a driving member mounted upon said shaft, a power control for said driving member, a top bar movably mounted in said frame, lifting members
20 carried by said top bar, a coöperating pressure roll carrying shaft movably mounted in said lifting members, pressure means disposed between said top bar, and the shaft of said pressure roll, meshing gears carried
25 by the pressure roll shafts, pivoted latches carried by said lifting members for holding said top bar in predetermined position within said frame, means carried by said latches engaging the gear of one of said
30 pressure roll shafts, a connection between said latches and said power control, said latches being actuated by the abnormal separation of said rolls for simultaneously releasing said pressure means, bodily raising
35 said roll, and actuating said power control.
24. A clothes wringer, comprising a frame having pressure rolls and pressure means for said rolls, a top bar movably mounted in said frame, lifting members carried by
40 said top bar connected to one of said pressure rolls, pivoted latches carried by said lifting members for holding said top bar in predetermined position within said frame, teeth carried by said latches adapted to engage one of the movable parts of said wringer when said latches are moved in position to release said pressure means, said latches being actuated on the abnormal separation of said rolls.
- 45 25. A clothes wringer, comprising a frame having pressure rolls and pressure means for said rolls mounted therein, one of said rolls and the pressure means being bodily movable toward and away from the other
50 roll, pivoted latches for holding said pressure rolls in contact under pressure, said latches being actuated by the abnormal separation of said rolls, and means carried by said latches coöperating with one of the
55 movable parts of said wringer for bodily raising said movable roll.
- 60 26. A clothes wringer comprising a frame having a movably mounted top bar, a pressure roll fixed in said frame, and a movably mounted roll carried by said top bar with 65 means for exerting pressure thereon, and means for holding said rolls in contact under tension.
27. A clothes wringer embodying a fixed roll, a coöperating roll movable toward and 70 away from the fixed roll, a movably mounted top bar having means for supporting said movable roll, and pressure means disposed between said top bar and said movable roll.
28. A clothes wringer, comprising a frame 75 having a fixed roll, a top bar movably mounted in said frame, lifting members carried by said top bar, a coöperating pressure roll mounted in said lifting members, pressure means disposed between said top bar and said coöperating pressure roll, and means for holding said top bar in position within said frame.
29. A clothes wringer, comprising a frame 80 having a fixed pressure roll, a top bar movably mounted in said frame, members carried by said top bar, a pressure roll movably mounted in said members and adapted to co-operate with the fixed pressure roll, pressure means for said movably mounted pressure roll, and means for holding said top bar in predetermined position within said frame for holding said pressure rolls in contact under tension.
30. A clothes wringer, comprising a frame 85 having pressure rolls and pressure means for said rolls, a top bar movably mounted in said frame having a connection with one of said pressure rolls and movable as a unit with said roll, and pressure means in said frame, and means for holding said top bar within said frame.
31. A clothes wringer, comprising a frame 90 having pressure rolls and pressure means for said rolls, one of said rolls being movably mounted toward and away from the other roll, said movable roll and pressure means being movable as a unit within said frame.
32. A clothes wringer, comprising a frame 95 having a movably mounted top bar, a pressure roll fixed in said frame, members carried by said top bar, a pressure roll movably mounted in said members, pressure means disposed above said movably mounted pressure roll, and means for holding said top bar in position within said frame for holding said pressure rolls in contact under tension.
33. A clothes wringer, comprising a frame 100 having a movably mounted top bar, and means for holding said top bar in predetermined position within said frame, a fixed pressure roll arranged within said frame, members carried by said top bar, a movable pressure roll mounted in said members, pressure means for said movable pressure roll, and means carried by said top bar for adjusting said pressure means.

34. A clothes wringer, comprising a frame having pressure rolls and pressure means, for said rolls, one of said rolls being movable toward and away from the other roll, and means for raising said movable roll and pressure means as a unit away from the other roll.

In testimony whereof I hereunto affix my signature in the presence of two witnesses.

EDGAR B. STOCKING.
